(57) **CLAIM**

The ornamental design for a staple cartridge, as shown and described.

DESCRIPTION

FIG. 1 is a perspective view of a staple cartridge, showing our new design without surface shading;

FIG. 2 is a top plan view thereof;

FIG. 3 is a bottom plan view thereof;

FIG. 4 is a right-side elevational view thereof;

FIG. 5 is left-side elevational view thereof;

FIG. 6 is a front elevational view thereof;

FIG. 7 is a rear elevational view thereof;

FIG. 8 is a perspective view of a staple cartridge, showing our new design with surface shading;

FIG. 9 is a top plan view thereof;

FIG. 10 is a bottom plan view thereof;

FIG. 11 is a right-side elevational view thereof;

FIG. 12 is left-side elevational view thereof;

FIG. 13 is a front elevational view thereof; and,

FIG. 14 is a rear elevational view thereof.

The broken lines in the drawings illustrate portions of the staple cartridge and form no part of the claimed design.
